FIG. 1 is a plan view of a shell for a filler neck crown taken perpendicular to the top, angled plane of the filler neck crown showing my new design;

FIG. 2 is a left side elevational view thereof, with the right side elevational view thereof being a mirror image thereof;
FIG. 3 is a view thereof taken in the direction of 3—3 of FIG. 2;

FIG. 4 is a top plan view thereof;

FIG. 5 is a bottom view thereof;

FIG. 6 is a fragmentary cross-sectional view thereof taken along line 6—6 of FIG. 3 showing the contour of the outermost visible surface;

FIG. 7 is a fragmentary cross-sectional view thereof taken along line 7—7 of FIG. 3 showing the contour of the outermost visible surface; and,

FIG. 8 is a fragmentary cross-sectional view thereof taken along line 8—8 of FIG. 3 showing the contour of the outermost visible surface.
